FIG. 1

FIG. 2

FIG. 1 is a perspective view, seen from the left front, of a combined meat and vegetable chopper embodying my new design; and

FIG. 2 is an elevational view thereof, seen from the right rear.

The side of the combined meat and vegetable chopper not shown in the drawing is mirror-symmetrical to that of FIG. 1 except that no switch structure is provided on the base at this side.

I claim:

The ornamental design for a combined meat and vegetable chopper, as shown and described.
